DESIGN FOR A BEDSTEAD

Sidney H. Tomlinson, High Point, N. C.

Application July 28, 1933. Serial No. 48,868

Term of patent 3½ years

To all whom it may concern:

Be it known that I, SIDNEY H. TOMLINSON, a citizen of the United States, residing at High Point, in the county of Guilford and State of North Carolina, have invented a new, original, and ornamental Design for Bedsteads, of which the following is a specification, reference being had to the accompanying drawing, forming part thereof, in which drawing—

Fig. 1 is a side elevation of a bedstead showing

my new design, with the center broken out for convenience of illustration;

Fig. 2 is an end elevation, looking from the foot end toward the head; and

Fig. 3 is a plan view of the same, with the center broken out for convenience in illustration.

I claim:

The ornamental design for a bedstead, as shown,

S. H. TOMLINSON.
